CLAIM

The ornamental design for a syringe handle for a medication administration device, as shown and described.

DESCRIPTION

FIG. 1 is a perspective view of a syringe handle for a medication administration device.

FIG. 2 is a bottom view of a syringe handle for a medication administration device.

FIG. 3 is a left side elevational view of a syringe handle for a medication administration device.

FIG. 4 is a front elevational view of a syringe handle for a medication administration device.

FIG. 5 is a right side elevational view of a syringe handle for a medication administration device; and,

FIG. 6 is a back elevational view of a syringe handle for a medication administration device.

The broken lines shown in the figures, including the indicia of FIGS. 1 and 3-6, are for the purpose of illustrating certain portions of the needle tip cap for a medication administration device and form no part of the claimed design.
